(57) **CLAIM**

The ornamental design for a video conference system as shown and described.

DESCRIPTION

FIG. 1 is a front perspective view of a video conference system without video display panels installed;

FIG. 2 is a back perspective view of the video conference system of FIG. 1;

FIG. 3 is a front view of the video conference system of FIG. 1;

FIG. 4 is a back view of the video conference system of FIG. 1;

FIG. 5 is a first side view of the video conference system of FIG. 1;

FIG. 6 is a second side view of the video conference system of FIG. 1;

FIG. 7 is a top view of the video conference system of FIG. 1; and

FIG. 8 is a bottom view of the video conference system of FIG. 1; and,

FIG. 9 is a front perspective view of the video conference system of FIG. 1, but further showing video display panels installed.

The dashed lines depict portions of the video conference system that form no part of the claimed design.

1 Claim, 7 Drawing Sheets
